UNITED STATES PATENT OFFICE.

JAMES BATE, OF DETROIT, MICHIGAN.

DIE-CASTING MACHINE.

Specification of Letters Patent. Patented Sept. 14, 1915.

1,153,749.

Application filed December 22, 1914. Serial No. 878,573.

To all whom it may concern:

Be it known that I, JAMES BATE, a citizen of the United States, residing at Detroit, in the county of Wayne and State of Michigan, have invented new and useful Improvements in Die-Casting Machines, of which the following is a specification.

My invention relates to an improvement in die casting machines, and particularly to an improved rotary mold or die carrier whereby a series of molds may be supported in such manner that any mold may be brought into position to receive a charge of metal from the metal supplying part of the apparatus.

The object of the invention is to provide a casting apparatus including a rotary die or mold carrier adapted to detachably and interchangeably receive dies or molds for casting a variety of work, whereby different dies may be applied for use and removed when desired and any die for casting any particular article easily, quickly and conveniently brought into communication with the metal supplying nozzle for the purpose of making the cast.

A further object of the invention is to provide a machine of the character described in which the dies when brought opposite the nozzle are adapted to be moved in position to receive the charge of metal therefrom by the action of a suitable die shifting device, operated by air pressure or other suitable means.

The invention consists of the features of construction, combination and arrangement of parts herein fully described and claimed, reference being had to the accompanying drawings in which:—

Figure 1 is a top plan view of a die casting apparatus embodying my invention. Fig. 2 is a side elevation of the same. Fig. 3 is a vertical section on the line 3—3 of Fig. 1. Fig. 4 is a vertical section on the line 4—4 of Fig. 3.

The apparatus includes a supporting bench or table 1, preferably mounted upon legs 2, and on which bench or table is mounted a suitable device 3 for supplying molten metal, discharged by means of a force feed device 4 through a nozzle 5, whereby the metal is forced into the forming cavity of the die or mold. The force feed device may be pneumatically or mechanically operated, no specific operating means being shown, as such does not constitute any part of the pres-

ent invention. The nozzle 5 is provided with a tapered end 6, for a purpose herein-after fully described.

Supported upon the table 1 is a turn-table or rotary die carrier comprising an annular or a ring-shaped bottom section 7 and an upper or carrier section or ring 8, the meeting faces of said sections being preferably grooved to form a raceway 9 for balls or other suitable anti-friction bearings 10, allowing the carrier section 8 to be easily revolved upon the section 7 which is rigidly fixed to the table 1. The nozzle 5 of the molten metal supplying device is arranged in juxtaposition to one side of the die carrier ring 8, at a point in its path of revolution, so that any of the dies or molds, which are mounted upon the ring 8, may be brought into position to receive a charge of molten metal from the nozzle.

As shown in the present instance, the ring 8 supports a series of dies 11, four of which are shown in the present instance, it being understood, however, that any desired or convenient number of dies may be mounted upon the carrier ring. The upper face of the ring is provided at stated points with dove-tailed transverse grooves or guide ways 12 to receive and engage the dove-tailed portions 13 on the bottom faces of the dies, by which each die is adapted to be slidably fitted in place by and removed in like manner, so that the dies will be rendered interchangeable for use. It will be understood that those dies which are employed most frequently may be mounted upon the carrier, and that when it is desired to employ a different die, the latter may be substituted for one of the dies carried by the ring. By this means a number of dies of a character most generally in use may be held at all times in readiness for operation, while the construction described admits of the substitution of other dies when occasion requires, thus enabling a wide range or variety of casting work to be performed in a ready and convenient manner upon one and the same machine.

Each die is provided with a forming chamber or cavity and is provided at its inner side with a tapered inlet 14 leading to said chamber or cavity and adapted to receive the tapered end 6 of the nozzle 5, so that by shifting the die with which the nozzle is in registry inwardly proper connection may be established between the die and

metal supplying device to supply the die chamber or cavity with the molten metal for making the desired kind of casting.

For the purpose of adjusting the dies into and out of working connection with the nozzle 5 I provide a die-shifter or actuating device comprising a vertically disposed lever 15, fulcrumed at 16 to the table for rocking motion in a direction toward and from the nozzle 5. The upper arm of this lever is adapted to engage the outer surface of a die or mold brought to a position between it and the nozzle 5, and may be detachably connected with the die or mold, so that by reverse movements of the lever the die or mold may be shifted into and out of engagement with the nozzle. The lower arm of the lever is coupled to the rod 17 of a piston 18 operating in a cylinder 19, which may be supplied with air from a suitable source for shifting the piston back and forth, whereby the lever will be operated on its reverse movements. Any other suitable automatic or manually controlled means for actuating the lever may, however, be employed.

In the operation of the device, it will be understood that one or more dies may be placed in position upon the rotary carrier, and that when it is desired to employ a particular die the carrier ring 8 is turned until the die is brought to a working position opposite the nozzle 5 and between said nozzle and the upper arm of the die actuating lever. Motion may then be communicated to the lever to force the die inwardly, thereby bringing the tapered end 6 of the nozzle 5 into engagement with the tapered inlet 14 of the die, so that upon the actuation of the expelling mechanism of the metal supplying device the charge of molten metal will be forced through the nozzle into the die for the carrying out of the casting action. One and the same die may be employed for casting any certain article, and when it is desired to make a different casting the die in use may be removed and the desired one substituted in its place, or the ring may be shifted around to bring any die of the series into working position. It will be understood that when the die and nozzle are engaged a locking action is set up by which these parts are maintained in fixed relationship for the

transfer of metal from one to the other, and that upon moving the upper arm of the actuating lever outwardly the die, if connected with the lever, will be moved outward by it, or if not connected with the lever may be moved outward by hand, thus breaking connection between the die and nozzle and permitting the carrier ring to be rotated to bring any other nozzle in position. By means of my invention any number of interchangeable molds may be conveniently employed for rapid casting and to enable various kinds of castings to be made on one and the same machine.

I claim:

1. In a die casting apparatus, the combination of a support, a die carrier ring mounted to revolve upon the support, said ring being provided at intervals with radial guideways, a metal supplying device disposed upon the support within the space bounded by the ring and provided with a tapered discharge nozzle, molds slidably mounted in said radial guideways and having tapered inlets to receive said tapered nozzle, and means for adjusting the dies inwardly to bring the inlet of a die into engagement with said nozzle.

2. In a casting apparatus, the combination of a support, a rotary ring-shape carrier mounted upon the support and provided with radial guideways, a metal supplying device mounted upon the support within the space bounded by the ring and provided with a tapered discharge nozzle, molds mounted in said radial guideways and each provided with a tapered inlet to receive the tapered nozzle, a lever pivotally mounted upon the support at a point in the path of movement of the rotary carrier ring, said lever having upwardly and downwardly projecting arms, the former being adapted to engage and shift the die inwardly to receiving position, and means operating upon the lower arm of the lever for moving said lever in its die shifting action.

In testimony whereof I affix my signature in presence of two witnesses.

JAMES BATE.
